Specification of Letters Patent.

Patented Mar. 7, 1922.

Application filed September 7, 1921. Serial No. 499,033.

To all whom it may concern:

Be it known that I, JOHN SILLARS BINNIE, St. Leonards, Kilmalcolm, Renfrewshire, Scotland, a subject of the King of Great Britain, have invented certain new and useful Improvements in Turbines, (for which I have applied for Letters Patent in Great Britain under date of Sept. 2, 1920, #25,322,) of which the following is a specification.

This invention has reference to turbines and the like of the kind wherein the pressure fluid is delivered as a jet, or stream through a nozzle, or bore, disposed at an acute angle relatively to the face of the rotor or to the tangent at that point of the outer periphery of the rotor on to which the fluid is delivered from the nozzle, or bore, and each blade of the rotor is provided with a curved surface against which is directed the jet, or stream, from the nozzle or bore.

In a turbine under this invention the rotor is provided with a series of blades separated from each other by inlet channels and outlet ports which communicate with each other, the ports being provided with outlet orifices of a depth greater than the inlet orifices to the channels, while the said inlet orifices are of a depth greater than the diameter of the bores of the nozzles through which the pressure fluid flows to the blades of the rotor.

In the present application, the depth of the channels and ports is the dimension measured in a plane at right angles, to the distance between the rotor blades, to the direction of the rotation of the rotor, and to the direction of the flow of the jets. The width of the channels and ports is the distance between two adjacent blades.

The application of the improvements under this invention applies to three types of turbine are illustrated by way of example in the accompanying drawings which form a part of this specification and in which:—

Figs. 1 and 2 are sectional views at right angles to each other of part of an inward flow turbine, showing some of the blades and a fluid nozzle.

Fig. 3 is a similar view to Fig. 1 showing the rotor with one of the blades disposed in an extreme position relatively to the nozzle, such extreme position being opposite to that shown in Fig. 1.

Fig. 4 is a similar view to Fig. 2 of a modified construction, and Fig. 4a a detail view thereof.

Figs. 5 and 6 respectively are plan and elevation of the preferred construction of blade under this invention for an inward flow turbine.

Figs. 7, 8 and 9 are similar views to Figs. 1, 2 and 3 of part of an outward flow turbine.

Fig. 10 is a side view of a preferred form of blade under this invention for an outward flow turbine.

Fig. 11 is a front elevation of part of a disc wheel provided with the improved construction and arrangement of blades and Fig. 12 is a section thereof taken through the nozzle and blades.

Figs. 13 and 14 are detail views of one manner of securing in position the arrangement of the blades shown in Figs. 1, 2, 3, 5 and 6.

As will be well understood, the fluid issuing from a bore or nozzle is not in the true sense a jet, but more closely resembles a rapidly moving stream or current, and for the purpose of this description, that part of the stream or current issuing from each orifice of each nozzle or bore and directed on the successive rotor blades is hereinafter referred to as a jet or stream.

By the improved construction and arrangement of rotor blades under this invention, the jets or streams pass from the nozzles or bores for comparatively considerable periods of time as complete jets or streams on to each successive blade, that is, the leading edges of the series of rotor blades are so spaced, that the jets or streams can operate on each succeeding blade for a considerable length of time as compared with that when the jets or streams are split by such leading edges.

As an example of approximate range of proportions for an hydraulic turbine between the cross sectional areas of the nozzle or bore and that of the discharging outlet, or discharge orifice of the port, with the construction hereinafter described, the ratio may vary as from about twice to five times the area of the nozzle or bore. With a gas or like fluid turbine the proportions will vary according to the known expansive properties of the fluid.

Referring to Figs. 1, 2 and 3 *a* designates the rotor which is of the drum type being provided with a flange *b* in which the blades and ports are provided. The bore or nozzle 5 *c* is shown arranged in the casing *d* of the turbine, and is so disposed that its centre line is at an acute angle to the tangent at the point of the rotor where the jet or stream impinges thereon. The blades are designated 10 *e* and each is provided with a curved front face *e*¹ which is, preferably, of the same radius throughout, an under rear side *e*² which may be of any suitable curve and an upper rear side or heel *e*³ along which 15 the channel *h* extends, the two rear sides approaching and being connected to each other.

The blades are disposed between the walls *b*¹ and *b*² of the rotor flange *b*, and between 20 each two adjacent blades is a port *f* which increases in width circumferentially and opens out at the discharge orifice *f*¹ into the chamber *g* within the rotor *a*, and at the other end communicates with a channel *h* 25 which leads into the clearance space *j* between the rotor flange *b* and the casing *d*. As will be seen in Figs. 1 and 2 the depth indicated by the line *y*, Fig. 2, of the outlet orifice of the port *f* is greater than the depth, indicated by the line *x*, Fig. 2, of the inlet orifice to the channel *h*, while the width, indicated by line *z*, Fig. 1, of the latter gradually increases towards the inlet orifice, at 30 which enters the jet or stream, from the bore, or nozzle. At the junction between the channels and the ports shoulders *k* are 35 provided.

In the construction illustrated the blades are separately constructed from the rotor, 40 being adapted for production from bronze or other non-corrodible metal shaped to the desired cross section.

In a preferred manner of construction, the blades are formed from rings the internal radius of which is that required for 45 the faces of the blades. A number of blades can be cut from the one ring and all have the same radius of front surface. It will be obvious that a number of such rings can be 50 formed from a single tube. One of such blades is shown in Figs. 5 and 6 and for the purpose of providing the channels *h* each section forming a blade is suitably grooved for this purpose. In forming such grooves 55 or channels *h* each blade is provided with horns *k* which are chamfered or bevelled off on the inner surfaces towards the exit end so as to provide a channel of gradually increasing depth towards such end. For the 60 purpose of insuring a good fit between adjoining blades, the outer corner of the horns are rounded off as at *k*¹ for fitting against the curved front surface *e*¹ at the adjoining blade. Where the blades are constructed 65 in this manner they are secured between the

flange *b*¹ forming part of the body of the rotor *a* and a shroud or retaining ring *b*² by bolts or rivets *l* as illustrated in Figs. 13 and 14, in which views the bolt or rivet is shown extending through the flange, the 70 blade and the retaining ring. The blades are preferably rounded on the rear surface at the junction *m* between the under rear side *e*² and the upper rear side or heel *e*³.

The depth of the ports *f* may be the same 75 from end to end, that is the opposite faces of the opposite walls *b*¹ *b*² or wall *b*¹ and ring *b*² may be parallel as shown in Fig. 2, or the ports *f* may increase in depth towards the outlet end and be provided with walls 80 *b*¹ *b*² the opposite faces of which are angularly disposed to each other as shown in Fig. 4.

With the construction shown in Figs. 4 and 4^a, the opposite side walls are angularly inclined towards each other to the 85 inlet end of the channel, thus providing an outlet of much greater depth than that of the inlet. By this arrangement the horns or shoulders *k* are dispensed with and a similar effect obtained by the converging sides as by the ports of suddenly increased depth with reference to the channels, the channels being constituted by those parts of the spaces between the blades which extend 90 along the heels of the blades and the remaining parts serve as the ports.

In the position of parts shown in Fig. 1 the blade *l* is so disposed as to be acted upon by the jet or stream discharged from the 100 nozzle or bore *c* with a maximum effort, that is, the whole jet or stream has just passed the leading edge *e*⁴ and the whole of it is 105 acting with practically the whole of its kinetic energy upon the curved surface *e*¹ of the blade, the only points at which any dissipation of kinetic energy due to "dead" fluid space, being in the clearance space.

By the operation of the jet or stream on blade *l* the rotor is turned from the position 110 of maximum effort to the position of minimum effort shown in Fig. 3, at which position blade 2 is in close proximity to the jet, or stream, with the upper rear side or heel *e*³ more or less parallel with the centre line 115 of the jet, and with its leading edge about to split the jet or stream. Throughout the whole time of its action upon each blade, the jet or stream practically acts upon the front surface of each blade and its kinetic energy 120 is more or less maintained, and its first action on each blade is as described with reference to Fig. 1, and from its first action it passes to the minimum effort action by reason of the rotation of the rotor. In thus 125 passing from one to the other, the "dead" fluid within the channel *h* and port *f* is more or less moved bodily therethrough and does not remain therein for the production of "eddy" currents. This moving of the 130

"dead" fluid is more or less brought about by constructing the channels of very slightly greater depth at the inlet orifice than that of the jet or stream and gradually increasing the depth of such channel in proportion to the increase in volume of the fluid due to the calculated decrease in velocity, and then providing a port of an increased depth adapted for the quick passage of the fluid to the discharge end thereof and into the chamber g after it has impinged on the rotor blade and expended the greater part of its kinetic energy thereon. It will be noted that where the blades are constructed as shown in Fig. 1, the jet or stream impinges on the front curved surfaces of the blades with the maximum effort of the kinetic energy whilst it is within the channel h and then immediately enters the port f , and that such jet or stream passes through a very small portion of the port f before impinging on the curved surface of the blade at the time of effecting its maximum effort. Thus the maximum amount of "dead" fluid space it has to pass through before impinging at the minimum effort is that comprised in the channel together with the small portion of the port f through which it passes, and to all intents and purposes it is only in the latter part of its travel i. e. in the small portion of the port f that any appreciable eddy currents will be formed.

As regards the increase in size of the channel h relatively to the diameter of the bore or nozzle a suitable increase is that wherein the channel is of rectangular construction of a depth the same as, or slightly larger than the diameter of the bore or nozzle through which the jet or stream passes to the channels.

The action of the fluid in the form of channel and port shown in Figs. 4 and 4^a is similar to that described above, as in this construction the ports constitute a continuation of the channels with the opposite sides diverging from each other and without the shoulders or horns. If desired, blades with horn portions may be used with divergent channels and ports.

The above description is made with reference to an inward flow turbine part of which is shown in the drawings as previously set forth, such description, however, applies generally to an outward flow turbine, parts of which are shown as previously stated, in Figs. 7, 8, 9 and 10. In this second construction, the blades are slightly modified to meet the altered conditions, the modification being apparent from the detail view of the blades shown in Fig. 10 however it may be pointed out that the upper rear side or heel e^3 of the blade e adjoining the leading edge e^4 is varied to the extent that it is not quite parallel with the centre line of the jet or stream when the latter is effecting its mini-

mum effort on the curved front surface e^1 of the blade, but it is angularly disposed away from the jet or stream when the latter engages with the leading edge e^4 of the blade, as will be apparent from Fig. 9. 70 Otherwise the blades are similar except that the upper rear side or heel e^3 is shortened for reasons which are obvious.

The provision of the form of construction of blade shown in Figs. 4 and 4^a has not 75 been illustrated in the drawings with reference to an outward flow turbine as it is considered such is unnecessary and the use of such form of blade in an outward flow turbine will be obvious from that already described with reference to Figs. 4 and 4^a.

The application of this invention to a turbine of the disc wheel type is illustrated in Figs. 11 and 12, wherein the rotor a is in the form of a disc with the blades e arranged on the periphery thereof and surrounded by a peripheral ring n . In this construction the disc a is preferably formed with a series of flats o on its periphery, one for each blade, to facilitate the attachment 90 of the blades thereto by screws, rivets or their equivalent l and as regards the attachment of the peripheral ring n , the disc with the blades secured thereto can be turned for the attachment of the ring thereto by shrinking on, or in any other suitable manner. It is to be understood that the disc wheel constructed according to this invention may have the blades formed integrally therewith and with the ring as may be the case with 100 the two constructions previously described, and may be formed with channels h and ports of gradually increasing depth or the channels may be formed with horns.

With the disc wheel construction the nozzle or bore is arranged at a suitable acute angle with the general plane of the disc, and the passages and ports between the blades will be transversely arranged to such plane.

In this construction of disc wheel, the 110 blades e are provided with a curved surface e^1 an under rear side e^2 and an upper rear side or wheel e^3 and between such blades are provided channels h and ports f in connection with which the jet or stream is adapted to 115 operate in a manner similar to that already described, that is, the channels are approximately the same or of slightly larger depth than the diameter of the bore or nozzle c and communicate with the high pressure 120 side of the disc on which side the nozzle or bore is disposed, while the ports f discharge into the low-pressure side. In this construction also the channels are shown provided with shoulders k these being constituted by the horns k and the latter are rounded off at their outer ends k^1 for fitment against the curved faces near the leading edges e^4 of the adjacent blade e .

As will be seen from the above descrip- 130

4
tion, the blades in each construction have the same characteristics of an upper rear side or a heel forming one of the sides of the more or less triangular form of blade, a curved front face to the blade of equal radius throughout and so arranged relatively to the heel of the adjacent blade as to provide a widened inlet orifice to the channel along the said upper rear side or heel where-
10 by the jets or streams are enabled to be directed on to the curved surfaces of the blades for considerable periods of time as complete and non-split jets or streams and thus enable an increased efficiency to be ob-
15 tained.

It is to be understood that the term fluid includes water, steam or gas or any other liquid or gaseous fluid.

Having now fully described my invention
20 what I claim and desire to secure by Letters
Patent is:—

1. A turbine comprising a jet nozzle and a rotor provided with a series of blades separated by channels and ports which communicate with each other, the series of channels being of greater depth at the inlet orifices than the bore of the nozzle and the series of ports being of greater depth at their discharge orifices than the depth of the inlet orifices to the channels, such depth being the dimension measured at right angles, to the direction of flow of the jet, and to the distance between adjacent blades.

2. A turbine comprising inlet nozzles and a rotor provided with a series of channels of greater depth at their inlet orifices than the bores of the nozzles and with a series of ports which communicate with the channels and are of greater depth at their discharge orifices than the depth of the inlet orifices of the channels.

3. A turbine comprising inlet nozzles and a rotor fitted with a series of blades which are arranged adjacently to each other with communicating channels and ports therebetween, the channels at the inlet orifices being of greater depth than the bores of the nozzles and the ports being of greater depth at their discharge orifices than the depth of the inlet orifices of the channels.

4. A turbine comprising inlet nozzles and a rotor fitted with a series of blades of approximately triangular shape arranged ad-

jacently to each other with an inlet channel and a communicating port between each two adjacent blades the depth of the discharge orifices of the ports being greater than the depth of the inlet orifices to the channels and the depth of the inlet orifices to the channels being greater than the diameter of the bores of the nozzles.

5. A turbine comprising a series of inlet nozzles and a rotor provided with a series of blades of approximately triangular shape arranged adjacently to each other with communicating channels and ports between them, the inlet orifices to the channels being of a depth greater than the diameter of the bores of the nozzles, and the ports being of greater depth at their discharge orifices than that of the inlet orifices to the channels, and the width of the channels being greater at the inlet orifices than where they communicate with the ports.

6. A turbine comprising a rotor fitted with a series of blades which are arranged adjacently to each other with channels and ports therebetween and each is of approximately triangular form having one side curved at the same radius throughout to serve as a front face and an upper rear side approximately straight and a suitably shaped under rear side, the two rear sides approaching and being connected to each other.

7. A turbine comprising a rotor fitted with a series of blades which are arranged adjacently to each other with channels and ports therebetween and each is of approximately triangular form having one side curved at the same radius throughout to serve as a front face and an upper rear side approximately straight and a suitably shaped under rear surface, the two rear sides approaching and being connected to each other and a casing in which the rotor is mounted and is provided with pressure fluid bores arranged to direct pressure fluid into the channels of the rotor.

In testimony whereof I affix my signature 100 in presence of two witnesses.

JOHN SILLARS BINNIE.
